(57) **CLAIM**

The ornamental design for a wench handle holder, substantially as shown and described.

DESCRIPTION

FIG. 1 is a front, perspective view of a wench handle holder showing my new design therefor;

FIG. 2 is a top plan view thereof with the bottom being a mirror image thereof;

FIG. 3 is a front, elevational view thereof;

FIG. 4 is a rear elevational view thereof; and,

FIG. 5 is a side-elevational view thereof with the opposite side being a mirror image thereof.

The broken line showing of a winch is for illustrative purposes only and forms no part of the claimed design.
